UNITED STATES PATENT OFFICE.

HAROLD A. BURT, OF ST. ALBANS, NEW YORK, ASSIGNOR TO MERGENTHALER LINOTYPE COMPANY, A CORPORATION OF NEW YORK.

TYPOGRAPHICAL DISTRIBUTING MACHINE.

Application filed May 12, 1928. Serial No. 277,146.

This invention relates to typographical distributing machines, such as linotype machines of the general organization represented in U. S. Letters Patent to O. Mergenthaler, 5 No. 436,532, wherein circulating matrices are released from a channeled magazine in the order in which they are to appear in print and then assembled in line, the composed line transferred to the face of a mold, the mold 10 filled with molten metal to form a slug or linotype against the matrices which produce the type characters thereon, and the matrices thereafter distributed according to character and returned through a channeled magazine 15 entrance to the magazine from which they started. In these machines, the magazine entrance is usually provided with a series of partitions which divide it into matrix channels and which are formed at their lower ends 20 with bent-over flanges arranged to guide the matrices by their projecting ears as they pass to the magazine (see the Butts Patent No. 1,099,486). These flanges are intended to direct the matrices regardless of thickness 25 properly into the magazine channels but it has been found that the thinner matrices for one reason or another get out of control and often tilt or vibrate as they pass into the magazine. While this condition, in any case, 30 is more or less objectionable, it becomes serious where the entrance channels are extremely wide, since the thinner matrices are allowed greater freedom both before and after they engage the flanges and frequently lodge 35 beneath the latter or are so delayed in their travel as to be overtaken by succeeding matrices.

The present invention is intended to obviate the above difficulties and contemplates 40 means whereby the matrices, whether thick or extremely thin, in passing through the entrance channels, will be positively guided by their projecting ears into a definite predetermined position before they are discharged. 45 In the preferred embodiment illustrated, such means include bent-over guiding flanges which are formed with straight guiding edges disposed in spaced parallel relation to the side walls of the channels and whose length 50 corresponds approximately to the length of the matrices. Light spring plates are also employed to guide the matrices by their side faces into proper engagement with the flanges, the said plates being sufficiently 55 strong to exert the required guiding effect

upon the thin matrices and yet flexible enough to be pushed aside by the thicker matrices without interrupting their passage (see the Kennedy Patent, No. 1,648,051).

In the accompanying drawings, the invention has been shown merely in preferred form and by way of example but obviously many variations and alterations may be made therein and in its mode of application which will still be comprised within its spirit. It 60 should, therefore, be understood that the invention is not limited to any specific form or embodiment except in so far as such limitations are specified in the claims.

Referring to the drawings:

Fig. 1 is a vertical section taken through the upper part of a linotype machine equipped with the present improvements;

Fig. 2 is a fragmentary view showing the relation existing between the entrance partitions and the magazine channels, the top plates of both entrance and magazine being omitted;

Fig. 3 is a comparative view, similar to Fig. 2, showing the regular construction; and

Fig. 4 is a detail perspective view of one of the entrance partitions with the improved matrix guiding means attached thereto.

The invention is herein shown as applied to a machine equipped with a multiple distributor which consists, in part, of the longitudinally ribbed or permuted bars B and the associated set of matrix conveying screws B¹. The matrices X are stored in the magazines A which are provided on the inner faces of their top and bottom plates A¹ with a series of opposing grooves a wherein the projecting ears x¹, x² of the matrices engage. Matrices released from the distributor bars are conducted to the magazine through the magazine entrances D, the latter each comprising the side plates D¹ and the intermediate series of partitions d which divide them into chutes or channels leading from the various bar combinations to the corresponding magazine channels. To facilitate the engagement of the matrix ears with the magazine grooves a, the latter are flared or widened, as usual, at their receiving ends (see Fig. 2), the intervening ribs a¹ being beveled off at one side from a predetermined point below the upper end of the magazine. The entrance channels are provided at their discharge ends with transverse flanges d¹ which overlap the flared portion of the grooves a and are intend-

ed to guide the matrices by their projecting ears just before they enter the magazines. These flanges may be formed directly on the partitions d or on separate plates secured to the partitions. So far as described, the parts are or may be the same as those presented in the patents to Butts or Kennedy before mentioned and to which reference may be had, if desired.

- 10 According to the present invention, the flanges d^1 are designed so as to engage simultaneously all four projecting ears x^1, x^2 of the matrices as the latter reach the discharge end of the entrance D, and in this way align 75
15 the matrices with the magazine grooves so that they may pass uninterruptedly into the magazine. The improved flanges as herein illustrated (see Fig. 4) are formed on separate pieces of sheet metal riveted or spot 80
20 welded to the partitions d near the lower ends thereof, and project transversely across the individual channels to within a given distance of the opposing partitions. The space thus provided, while wide enough to accommodate 85
25 the ears of the thickest matrices, is preferably made less than the combined width of the ears of two thin matrices so that only one matrix at a time may pass therethrough. As shown at the extreme left of Fig. 2, the straight 90
30 guiding edges d^2 of flanges are long enough to contact with both the upper and lower ears of the matrices and will, therefore, be capable of sustaining the latter in a perpendicular position flush against the partitions d until 95
35 they are discharged; it being noted that the upper ears x^1 of the matrices will be confined between the guiding edges d^2 and the opposing partitions d until the lower ears x^2 thereof have reached the restricted portion of the 100
40 magazine grooves a . The matrices are thus maintained under positive control, without danger of tilting or displacement, from the time they pass into engagement with the guiding flanges until they clear the discharge 105
45 end of the magazine entrance D.

- The advantages of the improved construction will be more easily recognized by reference to Fig. 3, which shows the old or regular type of guiding flanges. Here it will be noted 50 (like characters being used to indicate the corresponding parts), that the thin matrices in passing the flanges d^1 are momentarily free to tilt or vibrate as soon as their lower ears x^2 enter the flared portion of the magazine 110
55 grooves a and before their upper ears x^1 engage the upper inclined edges of the flanges d^1 . This condition is, of course, exaggerated in channels of extreme width and gives rise to the difficulties hereinbefore mentioned. 115
60 The upper edges d^3 of the improved flanges d^1 are also inclined at their upper ends and, in channels of moderate width, would in themselves suffice to direct the matrices by their projecting ears into engagement with 120
65 the straight guiding edges d^2 . In the pres-

ent instance, however, auxiliary guiding elements in the form of light spring plates E are provided and arranged in advance of the flanges to guide the matrices by their side faces. These plates are particularly advantageous in the wider channels and serve not only to prevent tilting of the matrices before they reach the flanges but relieve their impact with the inclined edges d^3 . As best shown in Figs. 1 and 4, the spring plates E are secured 75
at their upper ends to the partitions d below the receiving end of the entrance D and have their lower ends free and terminating above the guiding edges d^2 .

Having thus described my invention, its construction and mode of operation, what I claim and desire to secure by Letter Patent of the United States, is as follows:

1. In or for a typographical machine for handling matrices formed at their upper and lower ends with projecting ears, a matrix distributing chute or channel presenting opposite side walls for guiding the matrices by their side faces and provided at its discharge end with guiding means capable of engaging 90
both the upper and the lower projecting ears of the matrices simultaneously in order to maintain the matrices in a definite predetermined position before they are discharged.

2. In or for a typographical machine for handling matrices formed at their upper and lower ends with projecting ears, a matrix distributing chute or channel provided at its discharge end with flanges arranged to guide the matrices by their projecting ears, the said 100
flanges being of a length equal to that of the matrices so as to be capable of engaging both the upper and the lower ears of the matrices simultaneously before the latter are discharged.

3. In or for a typographical machine for handling matrices formed at their upper and lower ends with projecting ears, a matrix distributing chute or channel provided at its discharge end with flanges arranged to guide the 110
matrices by their projecting ears, said flanges presenting straight guiding edges disposed adjacent and parallel to the side wall of the chute, and said guiding edges being of a length equal to that of the matrices so as to be 115
capable of engaging both the upper and the lower ears of the matrices before the latter are discharged.

4. In a typographical machine for handling matrices formed at their upper and lower ends with projecting ears, the combination of a channeled magazine, and a channeled magazine entrance provided at its discharge end with flanges formed with straight 120
guiding edges for directing the matrices by 125
their projecting ears into the magazine channels, the said guiding edges being long enough to engage both the upper and the lower ears of the matrices before the latter are discharged into the magazine.

5. In or for a typographical machine for handling matrices formed at their upper and lower ends with projecting ears, a matrix distributing chute or channel provided at its discharge end with flanges arranged to guide the matrices by their projecting ears, and a resilient member readily displaceable by the passing matrices for guiding the matrices by their side faces into proper engagement with the flanges, the said flanges being of such length as to be capable of engaging both the upper and the lower ears of the matrices simultaneously before the latter are discharged.

6. In or for a typographical machine for handling matrices formed at their upper and lower ends with projecting ears, a matrix distributing chute or channel provided at its discharge end with flanges arranged to guide the matrices by their projecting ears and having straight guiding edges whose length equals that of the matrices, and a spring plate associated with the flanges for guiding the

matrices by their side faces into proper engagement therewith, the said spring plate being readily displaceable by passing matrices 25 and arranged with its lower end terminating in advance of the guiding edges of the flanges.

7. In or for a typographical machine for handling matrices formed at their upper and lower ends with projecting ears, a matrix distributing chute or channel provided at its discharge end with bent-over flanges arranged to guide the matrices by their projecting ears, and a resilient guiding member readily displaceable by the passing matrices for guiding 35 the latter by their side faces into proper engagement with the flanges, said flanges being formed with straight guiding edges disposed in spaced parallel relation to the side wall of the chute and whose length equals that of 40 the matrices, for the purpose described.

In testimony whereof, I have affixed my signature hereto.

HAROLD A. BURT.
